UNITED STATES PATENT OFFICE.

NORMAN W. NUTT, OF TRENTON, NEW JERSEY, ASSIGNOR TO TRENTON ELECTRIC AND CONDUIT COMPANY, OF TRENTON, NEW JERSEY, A CORPORATION OF NEW JERSEY.

ELECTRICAL FUSE-PLUG.

1,158,145.

Specification of Letters Patent.

Patented Oct. 26, 1915.

Application filed January 24, 1914. Serial No. 814,044.

To all whom it may concern:

Be it known that I, NORMAN W. NUTT, a citizen of the United States of America, and residing at Trenton, in the county of 5 Mercer and State of New Jersey, have invented certain new and useful Improvements in Electrical Fuse-Plugs, of which the following is a specification, such as will enable those skilled in the art to which it 10 appertains to make and use the same.

This invention relates to fuses in electrical circuits, particularly to plugs carrying such fuses and adapted for easy and instant installation or substitution, and the main object of this invention is to form a plug of 15 two parts jointly forming a chamber therein and means for readily connecting said parts together with the fuse therein.

A further object is to provide an element 20 which is adapted to visibly indicate the fact when the fuse has blown out.

Another object is to so form the constituent parts of my plug as to be interlocking against movement of one part on another but which readily permit taking the 25 plug apart to replace a burned out fuse.

A further object is to embed the fuse in asbestos or the like to take the flame and heat of a fuse when blown out; and other 30 objects are to form such fuses of conventional exteriors for use in standard sockets, which are very simple in construction, fully efficient, and comparatively inexpensive.

My invention is fully set forth in the following specification, of which the accompanying drawings form a part, in which the 35 separate parts are designated by the same reference characters in each of the views, and in which:—

40 Figure 1 is a plan view of a base provided with two of my improved fuse plugs; Fig. 2 is a section taken on the line 2—2 of Fig. 1; Figs. 3 and 6 are side and bottom plan views of one of the members of my plug; 45 Figs. 4 and 7 are side and top plan views of another member; and Figs. 5 and 8 side and bottom plan views of still another member which I employ.

In the drawings forming a part of this 50 application I have shown a present preferred method of accomplishing the desired results, embodying a socket member or base *a* provided with conductor clamps *b* and *c*, the former being connected with a plate *b*² 55 and center contact *b*³ which is insulated

from the plate *c*² of the clamp *c* by means of a washer *b*⁴, said plate *c*² being connected directly with the metal socket *c*³ and which is preferably screw-threaded internally, it being understood that the base *a* is formed 60 of insulating material, such as porcelain or the like.

My plug consists of a main portion *d* having a cavity therein and screw-threaded externally, the inner end being slotted transversely as shown at *d*², Figs. 3 and 6, and the outer end has a small recess *d*³ communicating with the interior of the part *d* by means of a small passage *d*⁴, a disk of paper or the like, *d*⁵, being placed in the recess *d*³ 70 for a purpose hereinafter pointed out.

In connection with the part *d* I provide a part *e* which has two side posts *e*² adapted to enter the slot in the member *d* whereby said parts are locked against rotary movement, one on the other, the circular portion of the part *e*, shown at *e*³, serving as a closure for the cavity in the part *d* and forming a substantially air-tight chamber *e*⁴, and centrally of the part *e* I provide a small 80 opening through the portion *e*³.

In conjunction with the part *e* I provide a metal disk *f*, adapted to rest on the center contact *b*³ when the plug is in position, said disk *f* having pliable fingers *f*², Fig. 2, 85 passed through the opening in the part *e* and being bent therein to lock said disk to the part *e*, and the fuse *f*³ is soldered to this disk, the fuse and disk being preferably though not necessarily provided in this 90 joined form, as the connection with the part *e* requires no skill and is instantly made.

When the parts *d* and *e* have been joined in the manner stated, an internally and externally screw-threaded sleeve is screwed on the part *d* to lock the members *d* and *e* against separation, this sleeve being designated by the character *h*, and I prefer to employ pliable fingers *h*² at the edge of the sleeve *h* which are adapted to be bent to enter recesses *h*³ on the part *e*, thus preventing accidental rotary movement of the sleeve when once in position, although it may be removed at will by merely straightening these fingers *h*². 100

In assembling my plug the fuse is first passed into the member *e* and the disk *f* secured in position as stated, the fuse being then laid over one of the posts *e*² of the member *e*, after which the members *d* and *e* 110

are joined together, the asbestos packing having been previously placed in the member *d*, and the sleeve *h* is then screwed over the members *d* and *e* and the fuse secured to the said sleeve in any desired manner, preferably by soldering, and my plug is ready for use, it of course being understood that the members *d* and *e* are of insulating material, such as porcelain or the like, whereas

10 the sleeve *h* is of conductive material.

The sleeve *h* adapts itself to the screw-thread of the member *d* and to the screw-thread of the socket *c*³ and a circuit is thereby established, from the clamps or binding 15 posts *b* and *c*, through the center contact *b*³, disk *f*, fuse, sleeve *h* and outer contact *c*³ and, in the event of the fuse blowing out, the fact is indicated by the burning or darkening of the paper disk *d*⁵ or, perhaps, by its 20 forcible removal from its normal seat by the explosion of the fuse; in such event the damaged plug may be quickly removed and another plug substituted therefor, repair of the damaged plug awaiting the pleasure or 25 opportunity of the electrician or engineer.

My invention is very compact, simple to manufacture, instantaneous in substitution, easy of repair by the insertion of a new fuse, the members are all locked together against 30 movement, and the device is very inexpensive and, while I have shown certain specific

details of the plug and of the socket base, it will be obvious that I do not limit myself thereto as various changes in and modifications of the same may be made without departing from the spirit of my invention or 35 sacrificing its advantages.

Having fully described my invention, what I claim as new, and desire to secure by Letters Patent, is:—

40 A fuse plug composed of two members joined together to form a chamber therein, one of said members having a transverse slot and the other member having a post projected into said slot to prevent rotary 45 movement of said members on each other, a sleeve threaded on said members to prevent longitudinal separation thereof, a contact disk at the bottom of said plug, and a fuse joining said disk and said sleeve, said post 50 and said slotted member having registering grooves jointly forming a passage for said fuse to reach said sleeve.

In testimony that I claim the foregoing 55 as my invention I have signed my name in presence of the subscribing witnesses this 22nd day of January, 1914.

NORMAN W. NUTT. [L. S.]
